BUCKLE

Paul Mariani, New York, N. Y.

Application November 30, 1938, Serial No. 243,100

2 Claims. (Cl. 24—178)

This invention relates to improvements in buckles, and more particularly to buckles for attaching to shoes, dresses and the like.

Objects

Among the principal objects which the present invention has in view are: to provide a shoe buckle of one piece construction; to enable imitation stones or the like to be held securely within a channel of a buckle; to provide a shoe buckle having fewer parts than required heretofore; to provide a shoe buckle of simplified construction and easily attached to a shoe; to secure simplicity of construction and operation and ease in manufacture; and to obtain other advantages and results as may be brought out in the following description.

Drawing

Figure 1 is an elevation of a shoe with a buckle of my improved construction as a part thereof;

Figure 2 is a sheet of blank metal material, shaped for assembling;

Figure 3 is a top plan of the buckle as in Figure 2 and showing the same as nearly completed;

Figure 4 is a transverse sectional view taken on line 4—4 of Figure 3;

Figure 5 is a completely assembled buckle and ready to be attached to a shoe;

Figure 6 is a view similar to Figure 5 and showing the buckle having a separate insert for the imitation stones; and

Figure 7 is a front elevation of the buckle.

Description

In the specific embodiment of the invention illustrated in said drawing reference numeral 10 designates in general the base or body portion of the buckle represented as being substantially rectangular with rounded corners in the present showing, but capable of being made in other shapes as will be understood by those versed in the art. The said body portion is preferably blanked out of a single piece of metal as indicated in Fig. 2, and the metal is appropriately stamped out to provide a central opening 11 therethrough having a contour substantially parallel to the outside contour of the blank. The edge margins of the metal are then bent to be perpendicular to the main part of the body portion, thereby forming outer rim 12 and inner rim 13 bent respectively on line 14 and 15 between which is accordingly provided a shallow channel 16. The bottom of this channel is impressed with a plurality of socket depressions 17 wherein the underside of jewels or imitation jewels 18

may be cemented. The rims 12 and 13 have a sufficient height to protect the jewel and to substantially engage the sides thereof to reduce the probability of dislodging the jewels by any inadvertent lateral scraping action against any other object.

The continuity of the inner rim of necessity is interrupted by portions of the metal which project inwardly of the opening, as indicated by narrow necks 18 which in turn are integral with more extensive ears 19, 19 ultimately curled, as shown in Figs. 5, 6 and 7 to embrace a pivot pin 20 upon which is mounted a tongue or pin 21.

The fabrication of my improved buckle contemplates making the rims 12 and 13 as nearly continuous as possible and as shown the outer rim is continuous around the entire periphery of the buckle. The inner rim is fabricated as shown in Fig. 2 with the ears 19, 19 separated at their end portions from the body portion by slits 22. Between the ends of the said slits 22, the metal between necks 18, 18 outwardly to the line of bending 15 is stamped and bent upwardly to form an upstanding tab 23 in alignment with and of the same height as bent-up rim 13. It will therefore be observed that this tab 23, except for the narrow necks, is a continuation of the upstanding inner rim and the metal which is required for making the tab leaves the small opening 24 between said tab and ear and between two narrow necks 18, 18 which retains the said ears integral with the body portion of the buckle. The pivot 20 butts at its ends against the opposite tabs 23, 23 and thus cannot slide out of position. The ears 19 curled around the said pivot keeps it from lateral displacement. Said ears 19, 19 are parallel to each other and separated a distance sufficient to receive the socketed end 25 of pin or tongue 21. The outer end of said pin 21 preferably projects across the end of the body portion and the face thereof opposed from the face having the channel and jewels. The said pin is preferably pointed so as to enable it to be inserted through the material forming a shoe 26 or other portion of attire on which the buckle is to be attached.

With particular reference to Figure 6, the invention is shown utilizing a two-piece construction. The body portion 10a is bent up as before except that the bottom wall of the channel is level, not having the socket depressions 17, but provides inner and outer rims, necks, ears, pivot and tongue all as previously described.

For mounting the jewels or imitation jewels 18 in this construction of Fig. 6, another or aux-

- iliary continuous channel member 27 is provided which will fit very exactly at its sides in the channel of the body member. The bottom of this auxiliary channel member has socket depressions for the jewels which may be cemented or otherwise held therein. In this instance, likewise, the rims around the inner and outer peripheries of the buckle protect the jewels from dislodgement, and in this instance the rims are both fully continuous entirely around their respective peripheries. The auxiliary member nests within the main body portion and may be suitably held therein by crimping, solder or other appropriate means.
- 15 I claim:
1. A buckle or the like comprising a body por-

tion having a continuous channel and substantially continuous side walls to the channel, a transverse pivot-pin between parallel portions of the channel, said side wall of the channel engaging the end of said pin for retaining it against longitudinal displacement.

2. A buckle or the like comprising a body portion having a continuous channel and substantially continuous side walls to the channel, a transverse pivot-pin between parallel portions of the channel, said side wall of the channel engaging the end of said pin for retaining it against longitudinal displacement, and ears integral with the body portion securing said pivot-pin against lateral displacement.

PAUL MARIANI.
